UNITED STATES PATENT OFFICE.

**CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.**

DESIGN FOR A RIBBON-CLAMP FOR LIGHT-REFLECTING BOWLS.

48,155.

Specification for Design.

Patented Nov. 16, 1915.

Application filed June 21, 1915. Serial No. 35,460. Term of patent 3½ years.

To all whom it may concern:

Be it known that I, CHARLES E. JONES, a citizen of the United States, residing at Chicago, in the county of Cook and State of Illinois, have invented a new, original, and ornamental Design for a Ribbon-Clamp for Light-Reflecting Bowls, of which the following is a specification, reference being had to the accompanying drawing, forming part thereof.

Figure 1 is a side elevation of a ribbon clamp for light reflecting bowls, showing my new design. Fig. 2 is a front elevation of the same.

I claim:

The ornamental design for a ribbon clamp for light reflecting bowls, as shown.

CHARLES E. JONES.
